Attorney

UNITED STATES PATENT OFFICE.

HERMAN BUSSEL, OF EL PASO, TEXAS.

METAL-BENDING MACHINE.

1,208,091.

Specification of Letters Patent. Patented Dec. 12, 1916.

Application filed March 27, 1916. Serial No. 87,037.

To all whom it may concern:

Be it known that I, HERMAN BUSSEL, a citizen of the United States, residing at El Paso, in the county of El Paso and State of Texas, have invented certain new and useful 5 Improvements in Metal-Bending Machines; of which the following is a specification, reference being had to the accompanying drawings.

10 This invention relates to an improved metal bending and shearing machine, and has for its primary object to provide a simple and easily operated mechanism whereby a metal bar may be readily bent to any desired angle.

15 It is a more particular object of the invention to provide a machine for the above purpose including a suitable base, standards rotatably mounted upon the base and arranged in juxtaposition to each other, each of said standards being slotted to receive the metal bar, the bar being adapted to be arranged in one of the standards whereby, when said standard is rotated, the 20 bar bearing against the other standard is angularly bent.

25 It is a further general object of the invention to provide a machine for the above purpose, embodying but few parts which are simple and durable in construction and capable of being easily and quickly assembled in operative position.

30 With the above and other objects in view, my invention consists in the novel features 35 of construction, combination and arrangement of parts to be hereinafter more fully described, claimed and illustrated in the accompanying drawing, in which,

35 Figure 1 is a perspective view illustrating 40 a metal bar arranged in position upon the machine to be bent; Fig. 2 is a top plan view showing the bar after it has been bent in the operation of the machine; Fig. 3 is a vertical sectional view taken on the line 45 3—3 of Fig. 2; Fig. 4 is a perspective view of one of the slotted posts or standards; and Fig. 5 is a detail perspective view of the 50 rectangular bending sleeve.

55 Referring in detail to the drawings, 50 designates the heavy, cast metal base, preferably, though not necessarily, of the form shown in Fig. 2. This metal base is provided in its approximate center with a vertically extending, rectangular opening 6 which tapers from its upper to its lower end. This opening 6 is adapted to be dis-

posed in registering relation over a socket in an anvil or other suitable support, and the anchoring pin or wedge 7 is driven through the opening and into the socket. In 60 the major portion of the base 5, a multiplicity of relatively small, equidistantly spaced, vertical openings 8 are formed for a purpose to be hereinafter referred to.

9 and 10, respectively, designate post 65 receiving openings extending vertically through the base 5. Each of these openings is diametrically enlarged adjacent its upper end to provide an annular shoulder 11 70 therein.

12 and 13 indicate the metal bending posts or standards which are of relatively different diameters and are provided upon one of their ends with reduced, cylindrical studs or extensions 14 and 15 respectively, for engagement in the openings 9 and 10 of the base 5. The body portions of the standards 12 and 13, at their juncture with the reduced studs, are of such diameter as to fit snugly within the enlarged upper end portions of the openings 9 and 10 and rest upon the shoulders 11. The metal bending posts or standards are identical in construction, and the description of one will, therefore, suffice for both. Each standard is provided 75 in its body portion with a longitudinally extending slot 16 which divides said body into spaced, parallel arms 17, each of which, at its upper end, has its outer peripheral face slightly beveled or tapered, as clearly shown 80 in Fig. 3 of the drawings. One of the arms 17 is provided with a series of spaced, threaded openings 18. The pivot studs on the lower ends of the standards which turn 85 in the openings provided in the base, are of 90 such length as to project slightly below the base 5. Upon these projecting ends of the pivot studs, collars or washers 19 are fitted and securely held in place by means of set screws 20, whereby the standards are held 95 100 against upward movement with respect to the base, and detachably retained in connection therewith.

A metal sleeve 21 is provided for each of the standards 12 and 13 and is adapted to 105 fit snugly thereover. By beveling the outer faces of the arms 17 of the standards as above explained, these sleeves may be easily and quickly slipped downwardly over the standards. In Fig. 5 I have shown a rectangular sleeve 22 which may be employed 110 when it is desired to make a square bend in

the metal bar. One side of this sleeve is adapted to be fitted into the vertical slot 16 of one of the posts or standards, one of the arms 17 projecting through said sleeve. 5 In the other side wall of the sleeve, a screw 23 is threaded, which is adapted to be engaged in any one of the threaded openings 18 so as to hold the sleeve in place against vertical movement. Only one of these 10 sleeves is necessary and is adapted to be fitted upon the larger of the posts or standards 12.

24 designates an operating lever which is provided with an annular head 25 on one 15 end, said annular head being of frusto-conical form and having a central, diametrically extending web or bar 26. This web is adapted to be received in the vertical slot 16 of either of the standards 12 or 13. The lever head 25 is fitted upon the upper tapering 20 ends of the arms 17 of the standard, the beveled or inclined peripheral faces of said arms binding against the longitudinally tapering inner wall of the annular head.

25 As clearly shown in Figs. 1 and 2 of the drawings, when it is desired to form an angular bend in a metal bar, the bar, after being suitably heated, is inserted edgewise downwardly into the vertical slot 16 of one 30 of the rotatable standards. The metal sleeve 21 is fitted upon the other adjacent standard, and the bar extends horizontally against one side of this sleeve. A set screw such as indicated at 27, may now be engaged in any 35 one of the openings 18 and adjusted into tight binding engagement with the metal bar to hold the same against longitudinal shifting movement on the standard. The operating lever is then applied to the upper 40 end of this standard and the said standard then turned or rotated upon the base in a direction toward that portion of the bar which bears against the metal sleeve 21 on the other standard. It will thus be obvious 45 that the bar will be bent in the manner shown in Fig. 2. When it is desired to insure the bending of the bar so that the two portions thereof will extend at angles of 90° with respect to each other, the rectangular 50 sleeve 22 is fitted into the slot of the standard 12 in which the bar is arranged. The sleeve is of considerably less thickness than the width of the slot, so that both the sleeve and the metal bar may be readily engaged 55 therein.

It is understood, of course, that the metal bar bears against one side of the other stand-

ard 13 so that when the standard 12 is rotated, the bar will be bent around one end of the sleeve 22 and in contact with the 60 face thereof so that the two portions of the bar will extend at right angles to each other.

From the foregoing description, taken in connection with the accompanying drawings, it is believed that the construction, 65 manner of operation and several advantages of my improved metal bending machine will be clearly and fully understood. The apparatus has been found highly satisfactory for all ordinary metal bending operations 70 and is especially designed for use by blacksmiths, wheelwrights, and similar mechanics, as it enables the operator to expeditiously perform the various metal bending operations which are frequently required. The 75 machine being of such simple construction may also be manufactured and sold at relatively small cost. It is apparent that the machine can be constructed in various sizes and a number of the metal bending posts or 80 standards may be provided having bar receiving slots varying in width so that metal bars of different thicknesses may be readily applied thereto and properly bent.

While I have shown and described the 85 preferred construction and operation of the several parts of the device, it is to be understood that the same is susceptible of considerable modification therein and I, therefore, reserve the privilege of adopting all 90 such legitimate modifications as may be fairly embodied within the spirit and scope of the invention as claimed.

Having thus fully described my invention, what I desire to claim and secure by 95 Letters Patent is:—

In a metal bending apparatus, a base, spaced rotatable posts removably mounted upon said base, each of said posts having a longitudinal slot opening upon the upper 100 end of the post into which a metal bar is adapted to be fitted, the other of the posts constituting a bearing for the bar, and a detachable lever adapted to be interchangeably engaged on the upper ends of said posts to 105 rotate the post within which the bar is fitted and angularly bend the bar.

In testimony whereof I hereunto affix my signature in the presence of two witnesses.

HERMAN BUSSEL.

Witnesses:

GEO. S. KIMBALL,
G. A. PERRY.
